DUAL CRYSTAL UNIT

Robert J. Jahrling, Jamaica, N. Y., assignor to
Premier Crystal Laboratories, Incorporated,
New York, N. Y.

Application March 15, 1943; Serial No. 14,938

7 Claims. (Cl. 171—327)

1.

This invention relates to piezo-electric crystal assemblies, and more particularly to a crystal unit adapted to provide a stable low frequency when connected to a suitable oscillator circuit.

A main object of the invention is to provide a novel and improved crystal unit of the dual-type which is especially adapted for use with dual oscillators to produce a stable beat frequency, such as an audio frequency, said unit having self-contained means for adjusting the resultant beat frequency by adjusting the frequency of one crystal.

A further object of the invention is to provide an improved dual crystal assembly embodying means for adjusting the beat frequency obtainable from oscillators controlled by the respective crystals when said oscillators are heterodyned, the assembly being very simple in construction, compact in size, and relatively inexpensive to manufacture.

A still further object of the invention is to provide an improved dual crystal assembly for use with heterodyning oscillators to provide a stable beat frequency, such as an audio frequency, the assembly being readily adjustable so that an exact beat frequency value may be obtained when the unit is employed as above described, the adjusting means being accessible from outside the unit, the unit being very rugged in construction and involving only a small number of parts.

Further objects and advantages of the invention will become apparent from the following description and claims, and from the accompanying drawings, wherein:

Figure 1 is a transverse vertical cross-sectional view taken through a dual crystal unit constructed in accordance with the present invention, said view being taken on line 1—1 of Figure 2.

Figure 2 is a horizontal cross-sectional view taken through the unit of Figure 1 on the line 2—2 thereof.

Figure 3 is a vertical cross-sectional view taken on the line 3—3 of Figure 2.

Figure 4 is a schematic diagram illustrating a first method of connecting the component elements of the crystal assembly of Figure 1.

Figure 5 is a schematic diagram illustrating a second method of connecting the component elements of the crystal assembly of Figure 1.

Figure 6 is a perspective view of the ground plate employed in the crystal unit of Figure 1, showing additional elements of the assembly secured thereto.

Figure 7 is an enlarged fragmentary cross-sectional detail view taken on line 1—1 of Figure 3.

2.

Figure 8 is a block diagram illustrating the manner in which the crystal unit of Figure 1 is employed with heterodyning oscillators to produce a desired stable beat frequency.

Referring to the drawings, the housing of the crystal unit is designated generally at 11 and comprises a base plate 12 of suitable insulating material and a cover member 13, also of insulating material, which is secured to the base plate by screws 14 which pass upwardly through base plate 12 and are threaded into the edge portions of the cover member 13. Designated at 15 is a vertical metal plate fitting closely between the opposite inside wall surfaces of cover member 13, plate 15 being formed with a horizontal bottom flange 16. Designated at 17 is a prong having a threaded shank portion 18 which passes upwardly through base plate 12 and through flange 16. Prong 17 is formed with a hexagonal collar 19 which bears on the bottom surface of base plate 12 and has threaded on the shank portion 18 a nut 20 which bears on flange 16, whereby plate 15 is tightly secured to plate 12 and prong 17 affords an electrical connection thereto.

Designated at 21 is a variable trimmer condenser of well-known construction, such as Centralab part 823-AN made by Centralab, a Division of Globe-Union Inc., Milwaukee, Wisconsin, said condenser being characterized by having a hexagonal stud 22 projecting from its central portion, in which is threaded the trimmer adjusting screw 23 which may be rotated by a screw driver to adjust the capacitance of the condenser. Projecting from the body of the trimmer 21 on opposite sides of the stud 22 are square metal studs 24, 24 riveted to the body of the trimmer, said studs 24, 24 being tapped to receive fastening screws. Designated at 25 and 26 are vertical insulating bars of substantial thickness and similar in shape. Bars 25 and 26 are formed at their lower ends with respective opposing arms 27 and 28 at their intermediate portions with respective opposing arms 29 and 30. Passing through arms 29 and 30 and through vertical plate 15 are fastening screws 31, 31 which threadedly engage the trimmed studs 24, 24 and secure the respective bars 25, 26 to the plate member 15 on one side thereof and the trimmer condenser 21 to said plate member on the other side thereof. The outer surfaces of the bars 25 and 26 are substantially flush with the edges of plate member 15 so that said outer surfaces are also closely fitted inside the cover member 13.

Plate member 15 is formed with a circular opening 32 through which stud 22 projects, said

stud being therefore positioned between the inwardly extending arms 29 and 30 of the bars 25 and 26. Threaded into the wall of cover member 13 in axial alignment with trimmer screw 23 is a removable plug 33. When plug 33 is unscrewed from the wall of cover member 13, a screw driver may be inserted into the unit to engage the trimmer screw 23 for adjusting the capacitance of trimmer 21.

Arms 29 and 30 define with the upper portions of bars 25 and 26, plate member 15, and the top wall of cover member 13 a rectangular cavity. Positioned in the cavity adjacent plate member 15 is a first crystal plate 34. Positioned adjacent the side edges of crystal plate 34 are vertical spacer bars 35, 35 of insulating material, such as glass, slightly greater in thickness than crystal plate 34. Bearing on the spacer bars is a metal electrode 36 which closely fits into the cavity, said spacer bars providing a small air gap between the electrode 36 and the crystal plate 34. Secured to the bars 25 and 26 is a metal strap member 37 which bridges the cavity in which the crystal plate 34 and the electrode 36 are contained. A coiled spring 38 is positioned between electrode 36 and strap member 37, whereby electrode 36 is firmly held in abutment with the spacer bars 35.

Arms 27 and 28 define with arms 29 and 30, the lower portions of bars 25 and 26, and plate member 15, a second rectangular cavity. Positioned in said second cavity adjacent plate member 15 is a second crystal plate 39. Positioned adjacent the side edges of crystal plate 39 are additional vertical insulating spacer bars 35, 35 slightly greater in thickness than plate 39. An electrode 40 is fitted in said second cavity and bears on the spacer bars 35, 35 therein. A second strap member 41 is secured to bars 25 and 26, which bridges said second cavity. A coiled spring 42 is positioned between electrode 40 and strap member 41, whereby electrode 40 is firmly held in abutment with the spacer bars 35, 35 in the second cavity.

Designated at 43 and 44 are additional prong members secured to base member 12 parallel to prong member 17, said prong members having hexagonal collars shown respectively at 45 and 46 and threaded shanks passing through base member 12, on which respective nuts 47 and 48 are threaded.

The crystal plates 34 and 39 are matched in frequency and have identical temperature-frequency characteristics. The assembly may be wired in either the manner shown in Figure 4 or the manner shown in Figure 5. In Figure 4, crystal electrode 36 is connected by a wire 49 to prong 43 and crystal electrode 40 is connected by a wire 50 to prong 44. The trimmer condenser 21 is connected in parallel with crystal 34, one terminal of the condenser being connected to plate member 15 and the other terminal thereof being connected to the prong 43.

In Figure 5 the trimmer condenser 21 is connected in series with crystal 34 instead of being connected in parallel therewith as shown in Figure 4.

Figure 8 discloses the manner in which the unit is connected to an external circuit in order to provide a desired audio frequency output signal. The circuit comprises a first oscillator 51 and a similar second oscillator 52. The prongs 17 and 43 are connected to the input terminals of oscillator 51 and the prongs 17 and 44 are connected to the input terminals of oscillator 52. The output terminals of the oscillators are connected to the input circuit of a mixer stage 53 wherein the

frequencies of oscillators 51 and 52 are heterodyned, providing a low frequency beat signal at the output terminals of said mixer stage. By adjusting the trimmer condenser 21 in the manner above described, the beat signal may be made to have any desired audio frequency. Since the crystals have identical frequency-temperature characteristics, the derived beat frequency will remain constant in value over a considerable range of temperatures.

Heretofore where crystal controlled oscillators have been employed to provide a stable beat frequency, the crystals controlling the respective beating oscillators were physically in different environments, and although the crystals may have had identical temperature-frequency characteristics, variation in the respective temperatures of the crystals has not been necessarily the same for both crystals. This has produced a substantial degree of instability of the beat frequency thus derived, especially where said beat frequency was of a low audio value. Where it was necessary to maintain stability of the audio frequency within close limits, the above described heterodyne method has been unsuccessful because even a few degrees variation in temperature between the crystals has resulted in many cycles of difference in the derived audio beat frequency. In the unit of the present invention, both crystals are in close physical contact with the metal ground plate 15, and although the temperature of said plate may vary, there is no difference in the temperature of the crystals. Therefore, once the beat frequency has been established by the adjustment of the trimmer condenser 21, the beat frequency will remain constant regardless of external temperature conditions.

While a specific embodiment of a dual crystal assembly for use in beat frequency oscillator circuits has been disclosed in the foregoing description, it will be understood that various modifications within the spirit of the invention may occur to those skilled in the art. Therefore it is intended that no limitations be placed on the invention except as defined by the scope of the appended claims.

What is claimed is:

1. A dual crystal holder comprising a base, an upstanding metal plate member secured to said base, a pair of insulating bars secured to opposing marginal portions of said plate member on one side thereof, said bars being formed with pairs of opposing projections defining with respect to said plate member a pair of crystal-receiving cavities, said plate member being formed between one pair of said opposing projections with an opening, and an adjustable impedance secured to the opposite side of said plate member and having an adjusting element aligned with said opening.

2. A dual crystal holder comprising a base, an upstanding metal plate member secured to said base, a pair of insulating bars secured to the side marginal portions of said plate member at one face thereof, said bars being formed with inwardly projecting opposing arms defining an upper and a lower crystal cavity, said plate member being formed between one set of opposing arms with an opening, and an adjustable impedance secured to the opposite face of said plate member and having an adjusting element aligned with said opening.

3. A dual crystal holder comprising a base, an upstanding metal plate member secured to said base, a pair of insulating bars secured to the side marginal portions of said plate member at one

75

face thereof, said bars being formed with inwardly projecting opposing arms defining an upper and a lower crystal-receiving cavity, said plate member being formed between the opposing arms intermediate the cavities with an opening, and an adjustable condenser secured to the opposite face of said plate member and having an adjusting element aligned with said opening.

4. A dual crystal holder comprising an insulating base, an upstanding metal plate member secured to said base, a pair of vertical insulating bars secured to the side marginal portions of said plate member at one face thereof, said bars being formed with intermediate opposing arms and bottom opposing arms defining an upper rectangular space and a lower rectangular space adjacent said one face of the plate member, said plate member being formed between the intermediate opposing arms with an opening, and an adjustable condenser secured to the opposite face of said plate member and having an adjusting element projecting through said opening.

5. A dual crystal unit comprising a base, an upstanding metal plate member secured to said base, a pair of vertical insulating bars secured to the side marginal portions of said plate member at one face thereof, said bars being formed with intermediate opposing arms and bottom opposing arms defining an upper rectangular space and a lower rectangular space adjacent said one face of the plate member, said plate member being formed between the intermediate opposing arms with an opening, an adjustable condenser secured to the opposite face of said plate member and having an adjusting element aligned with said opening, a crystal plate positioned in each space substantially in contact with said metal plate member, an electrode positioned in each space

outwardly adjacent the crystal plate therein, means secured to the outer surfaces of the bars in bridging relation to said spaces, and respective springs positioned between said means and the respective electrodes.

5 6. A dual crystal holder comprising a base, an upstanding ground plate secured to said base, insulating means secured to one side of said ground plate and formed to define two crystal-receiving cavities with the ground plate as the inner wall of said cavities, said insulating means also defining a space intermediate said cavities, said ground plate being formed with an opening at said intermediate space, and an adjustable condenser secured to the opposite side of said ground plate and having an adjusting element aligned with said opening.

10 7. A dual crystal holder comprising a base, a ground plate secured to said base, insulating means secured to one side of said ground plate and formed to define two crystal-receiving cavities with the ground plate as the inner wall of said cavities, said ground plate being formed with an opening adjacent said cavities, and an adjustable condenser secured to the opposite side of said ground plate and having an adjusting element aligned with said opening.
